UNITED STATES PATENT OFFICE.

ARTHUR S. MILINOWSKI, OF BROCKPORT, NEW YORK.

CALCULATING-MACHINE.

1,310,204.

Specification of Letters Patent. Patented July 15, 1919.

Application filed October 10, 1914. Serial No. 865,987.

To all whom it may concern:

Be it known that I, ARTHUR S. MILINOWSKI, of Brockport, in the county of Monroe and State of New York, have invented certain new and useful Improvements in Calculating-Machines; and I do hereby declare the following to be a full, clear, and exact description of the same, reference being had to the accompanying drawings, forming a part of this specification, and to the reference-numerals marked thereon.

My invention relates to calculating machines and it has for its object to provide an improved construction to be embodied in such a mechanism as part of a unitary structure or to be used as an independent unit that coöperates with the calculating mechanism by means of convenient operative connections, and it has for its purpose to simplify the operation and control of this sort of a machine. A further object of the invention is to provide a structure involving comparatively few parts that coöperate in such a manner as to greatly reduce the number of operations necessary in working the usual types of calculating machines. Another purpose of the improvement is to afford a simple mechanism that can be applied to an adding or calculating mechanism without requiring reconstruction of the latter and which can be operated readily and speedily. To these and other ends the invention consists in certain improvements and combinations of parts all as will be hereinafter more fully described, the novel features being pointed out in the claims at the end of the specification.

In the drawings:

Figure 1 is a plan view showing the application of my invention to one of the usual forms of eighty-one key type calculating machines;

Fig. 2 is a rear elevation of the mechanism;

Fig. 3 is a front elevation of the parts shown in Fig. 2 with a portion of the casing removed;

Fig. 4 is a vertical sectional view on the line 4^a—4^a of Fig. 2;

Fig. 5 is a vertical sectional view on the line 5^a—5^a of Fig. 2, showing the position of the parts after two of the actuating devices have been set while the controlling key for a third one of the actuating devices is in its depressed position prior to being released;

Fig. 6 is horizontal sectional view on the line 6^a—6^a of Fig. 5;

Fig. 7 is an enlarged detail view of the stop carrier;

Fig. 8 is a sectional view on the line 8^a—8^a of Fig. 2, and

Fig. 9 is a sectional view on the line 9^a—9^a of Fig. 2.

Similar reference numerals throughout the several figures indicate the same parts.

The invention is herein illustrated according to a practicable embodiment, merely by way of example, and it will be understood that it may be carried out in other ways, and still adhere to the fundamental principle of a series of controlling keys, each of which is adapted and arranged to selectively preposition any one of a series of actuators governing the calculating members which may be in the form of keys, wheels or other equivalent calculating units and as a means by which the invention may be successfully carried out, I have shown the structure operatively combined with an eighty-one key type of adding machine, although it will be understood that my invention is not to be limited to a calculating or adding machine of this particular character or in the relation illustrated, inasmuch as it may be included as a part of the calculator structure rather than as an operatively connected separate mechanism, or it may also be applied in more direct connection with a registering mechanism.

In the embodiment which I have shown to illustrate my invention, 1 designates a calculating machine provided with a series of banks of keys 2 by which the operating mechanism for the various numbers is set, as well known in this class of machinery, while 3 is the actuating lever for effecting operation of the adding instrumentalities, the same being provided with an operating handle 4. The mechanism which characterizes the present improvements is contained within a casing 5 and includes a series of actuating devices designated at 6 and mounted on a traveling support 7 all as will be presently described more clearly. The structure thus includes a series of key controlled actuating devices, of which there are nine in the arrangement described, and these are arranged so that each one may be brought into coöperative relation with any one of the calculating units with which it is designed to engage, or as applied to the structure illus-

trated, with any key of any one of the banks or series of keys of the calculating mechanism. For this purpose, there is a connecting lever for each one of the keys of the calculating mechanism, as designated at 8, the levers for the different banks of keys being pivoted in different horizontal planes and the levers for each bank of keys being pivoted on a common bearing 9, so that when the actuating devices are operated in a manner which is to be hereinafter described, the connecting levers 8 will be moved to set the corresponding keys 2 of the calculator. Upon reference to Fig. 1, the arrangement and construction of the connecting levers for each bank of keys can be seen, two of the sets of levers being shown in the figure referred to. The central connecting lever 8 pivots about the axis 9 which is suitably secured in the walls of the casing 10, while 8^a, 8^b, 8^c, 8^d, 8^e, 8^f, 8^g and 8^h indicate the connecting levers on opposite sides of the central one, these being connected to the several keys of one bank of the calculator. It will be observed that with the exception of the central connecting lever, the levers comprise offset portions as, for instance, 8^a and 8^f, or 8^b and 8^g, each of which pivot about the common axis 9 and are connected by suitable braces 8^k. The portion 8^a is provided with an enlarged opening 8^l to receive the brace 8^g which passes therethrough and connects portion 8^b with 8^h. The connecting levers 8 to 8^h inclusive coöperate with the keys of the calculator representing the numeral 9 and whenever the "nine" key of the controlling mechanism is operated, one of the actuating devices will be moved into a plane for coöperation with one of the levers 8, 8^a, etc., and in the final totaling operation, the corresponding key 2 of the calculator will be set. In this manner, it is possible to effect the operation of any nine or less of the calculating members by operating a corresponding number of controlling keys of which only one set are provided, thus greatly reducing the cost of the mechanism and increasing the simplicity of its operation.

The parts which I have thus far described relate principally to the operative connections between the actuating devices of my invention and the operating keys of a calculating machine and I will now proceed to describe the construction and operation of the parts through which the positioning of the actuating devices is effected.

The actuating devices, designated at 6, are mounted on a support which is longitudinally movable of its axis and consists of a sleeve 7, mounted on a rotary spindle or shaft 12. The spindle 12 is provided with a cam groove or way 13 which coöperates with a key 14 carried by the sleeve 7 so that as the spindle is rotated, in the manner which will presently be described, the support for

the actuating devices is advanced a predetermined distance at each operation to bring the actuating devices successively into setting position. Each of the actuating devices comprises an operating portion 14 for engagement and coöperation with one of the corresponding connecting levers 8, and a locking portion or tail piece 15 which is engaged by the locking stop and the positioning stops, presently to be described and serves to maintain the actuating device in the position to which it is set. A spring 16 connects each actuating device with a bar 17 secured between arms or extensions 18 on the support 7 and exerts a tension constantly, tending to move the actuating device until its movement is limited. In order to afford a general understanding of the method of setting the actuating devices, it may be stated that they are normally held in position, in horizontal alinement with each other, by a common locking stop and at each operation of a controlling key, the locking stop is moved to release one of the actuating devices. At the same time, a positioning stop, corresponding to the key which is operated, is moved into the path of the released actuating device which is then moved by its spring until its locking portion engages the positioning stop referred to. During the operation just described, the traveling support is advanced a step and another actuating device is brought into setting position, means being provided for retaining the previously set actuating device in its set position until the entire number has been set up.

To this end, I provide an oscillatory stop carrier which comprises a pair of end plates 19 journaled on the bearings 20 and connected by suitable brace rods 21. The carrier is held in its normal position by means of a spring 22 connected to it and to the casing as shown in Fig. 2. Arranged between the end plates of the carrier are the locking and positioning stops which consist of oscillatory bars, and in the present embodiment, 23 designates the locking stop, as shown in Figs. 2, 4 and 7, which is normally in the position shown in Fig. 2, having engagement with the locking portions of the several actuating devices. The locking stop is provided with a cutaway portion 24 affording a flat face co-extensive with the actuating devices which permits the latter to pass freely thereover when the locking stop is moved to the proper position. At one end of the cutaway portion 24 is a recess 25 which is of the width of one of the actuating devices and is so arranged with relation to the other parts of the locking stop that it permits one of the actuating devices to pass freely thereacross when in the setting position, as shown in Fig. 5. In order to provide for the operation of the locking stop, it carries arms 26 to which are connected a spring 27 having its

- opposite end attached to the casing and serving to hold the locking stop normally in the position shown in Fig. 2. The arm 26 is operated to release the actuating device by means of a bar 28 which is carried by a rocking frame 29 pivoted at 30 and carrying a horizontal bar 31 by which it is actuated through the controlling keys in a manner that will presently be set forth.
- 10 Each of the positioning stops preferably comprises a bar 32 that is cylindrical for a portion of its length and is recessed or cut-away to afford a flat face coextensive with the actuating devices when the latter are in normal position and permitting them to pass thereover, and when the support is advanced to bring an actuating device opposite the cylindrical portion of a positioning stop, said cylindrical portion retains the actuating device in its set position by engagement with the locking portion thereof. There are nine positioning stops, the uppermost one 32^a corresponding to the "one" key, the next lower one 32^b corresponding to the "two" key, and so on down to 32ⁱ which corresponds to the "nine" key, the recess or cutaway portion of the stops, already referred to, being designated at 33. The several positioning stops are rotatively mounted on the carrier with the exception of the uppermost stop 32^a which is fixed within the carrier and cylindrical throughout. This is for the reason that the uppermost stop determines the highest position of the actuating devices and in resetting, the locking portions of the actuating devices are moved away from the last mentioned positioning stop and over the flat faces or recessed portions of the underlying positioning stops. Each of the positioning stops from 32^b to 32ⁱ inclusive has fixedly mounted thereon a slotted arm 34 engaged by a pin or projection 35 on the keyplate 36 of the controlling means. The controlling means includes nine keys 37, from 1 to 9 inclusive, each mounted on a key-plate 36 and operating when depressed to oscillate the corresponding positioning stops 32 and at the same time to move the locking stop so as to release the actuating device. To this end, the key-plates 36 extend downwardly to a point adjacent to the rod 31 so that when any key is operated, said rod is lowered, moving the rocking frame 29 and thereby oscillating the locking stop. Since the positioning stop for the "one" key is fixedly mounted on the carrier, there is no necessity for any connection, and when the "one" key is operated, it serves merely to move the locking stop, and permit the actuating device to move until its locking portion is in the uppermost position, as illustrated in Fig. 5. In the figure referred to, the actuating devices corresponding to the "one", "five" and "eight" keys have been set, the "five" key being shown in its lowered position just be-
- fore release. The key-plates 36 are mounted on links 38 which are pivoted on the shafts 39 while 40 are springs connected to the links and to a stationary support and operating to return the key-plates and also the stops to normal position. It will be noted that the carrier moves step by step to carry the actuating devices into denominational position independently of any movement of the cylindrical stop bars. The actuating devices move on the carrier into engagement with the stop bar which has been actuated to coöperate therewith and which stop bar retains the actuating device in "set" or numerical position while the carrier moves it step by step into denominational position. These stops are universal stops since there is but a single stop for each numerical position of the actuating device and all the actuating devices coöperate with the same stop when set to a given numerical position.
- 15 20 25 30 35 40 45 50 55 60 65 70 75 80 85 90 95 100 105 110 115 120 125 130
- At each operation of a controlling key, the support for the actuating devices is advanced to bring the next adjacent actuating device into setting position, and to this end the spindle 11 is provided with a ratchet wheel 41 and coöperating therewith is a pawl 42 which is pivotally mounted on the arm 43 journaled about said spindle and connected by a link 44 to a bell-crank 45 which is pivoted at 46. The horizontal portion of the bell-crank 45 is engaged by the bar 31, and when the rocking frame 29 is operated, the bell-crank 45 is thereby rocked causing the pawl 42 to move over the ratchet wheel 41 far enough to engage another tooth and cause the spindle 11 to be rotated a quarter of a turn when the bell-crank 45 is returned to its normal position by the spring 47.
- When the number to be added includes a zero, it is only necessary to move the support one step so as to change the denominations of the actuating devices that have been previously positioned, and to this end I provide a zero key 48 which is pivoted at 49 and operatively connected to the bell-crank 45 by means of a slotted end portion 50 that engages a projection 51 on the bell-crank. By this means, an operation of the zero key 48 serves to effect a quarter of a revolution of the spindle 11 and thereby advance the support on which the actuating devices are mounted.
- After the several actuating devices in any given number are positioned and held in place by the cylindrical portions of their respective positioning stops, the stop carrier is rocked causing a simultaneous movement upwardly of the operating portions 14 of the actuating devices that have been set, and a corresponding movement of the keys of the calculator through their connecting levers 8. This movement of the carrier is accomplished in the following manner. A shaft 52 is mounted in the lower part of the cas-

ing and is connected to the lever 3 of the calculator by means of a crank 53 and connecting rod 54. The shaft 52 carries a collar 55, provided with a cam 56 adapted to engage a cam portion 57 on the stop carrier. Thus when the lever 3 is operated, it rocks the shaft 52 and through the cam 56 causes an upward movement of the lower portion of the stop carrier and since the actuating devices are held in predetermined position by the several stops on the carrier, the actuating devices will be correspondingly moved. It is desirable to return the support for the actuating devices to its normal or initial position during the continued rotative movement of the shaft 52, and to this end I provide means for rotating the spindle 11 in a reverse direction. The latter carries a pinion 58 which meshes with a gear 59 mounted on a shaft carrying a pinion 60 which is mutilated for a portion of its periphery for a purpose that will appear presently. Loosely mounted on the shaft 52 is a gear segment 61 which is provided with a slot 62, and fixedly mounted on the shaft 52 is an arm 63 having a pin or projection 64 for engagement in said slot, so that during the rotation of the shaft 52, when the projection 64 reaches the upper extremity of the slot 62, it engages the gear segment moving it laterally, and rotating the mutilated pinion 60 until the mutilated portion is brought to its normal position as shown in Fig. 8. Through the gearing already described this causes a rotation of the spindle 11 in a reverse direction and returns the support to its initial position. During the reverse movement of the spindle 11, the pawl 42 is held out of engagement with its ratchet by the slot 64^a in the gear segment 61, the pin 64^b of the pawl riding upwardly over the edge of the gear segment and into the slot 64^a, as will appear from Fig. 8.

It then becomes necessary to return the actuating devices to their normal positions on the support and this is accomplished by a resetting means during the return movement of the shaft 52 in the following manner. 65 designates a resetting frame which is journaled about the spindle 11 and carries a bar 66 adapted to engage the operating portions of the actuating devices and to return them to their upper positions as shown in Fig. 2. The resetting frame is connected 55 to a plate 67 by means of a rod 68, said plate being journaled on the spindle 11 and provided with a toothed portion 69. 70 is a toothed segment fixed on the shaft 52 and operating during the return movement of 60 the latter to engage the toothed portion 69 of the plate 67, thereby elevating the bar 66 far enough to return all of the actuating devices into engagement with the locking stop. The resetting frame is returned to 65 its normal position by means of a spring 71

which is connected to the plate 67. During the latter part of the movement of the resetting frame, it is also desirable to operate the locking stop so as to bring the cutaway portion 24 into position to permit the actuating devices to pass thereover. This I accomplish by providing the locking stop at one end with a lug 72 which is arranged to be engaged by a yieldable pawl 73 pivotally mounted on the plate 67 and controlled by 75 the spring 74 which holds the pawl against the stop 75 during its operative movement whereby the lug 72 is engaged and the locking stop oscillated. The spring 74 permits the pawl 73 to ride freely over the lug 72 80 during the return movement of the plate 67 after it is released by the gear segment 70.

The operation of the construction of the present embodiment, briefly described, is as follows. It will be supposed that it is desired to add the number "1850" to a series of numbers that have previously been set up in the calculator. The "one" key of the controlling keys is depressed causing the locking stop to be turned until the recess 90 25 is in position to permit the first actuating device to pass therethrough. The latter is then moved by its spring to the uppermost position as shown in Fig. 4 and at the same time, the support is advanced a step 95 to bring the second actuating device opposite the notch 25. The "eight" key is next operated causing a simultaneous oscillation of the locking stop and of the positioning stop 32^b which corresponds to the "eight" 100 key. The actuating device is permitted to pass through the recess 25 but is engaged by the positioning stop 32^b as shown in Fig. 5, the latter having been turned sufficiently to move the recessed portion 33 out of the 105 path of the locking portion of the actuating device. Before the positioning stop is returned to its normal position, the support is advanced another step, bringing the last mentioned actuating device into engagement 110 with the cylindrical portion of the positioning stop, as will be seen from Fig. 5. The operation of the "five" key is similar to that of the "eight" key just described, with the exception that the locking portion of 115 the actuating device is engaged by the positioning stop 32^c. For the "zero," the "zero" key 48 is operated, advancing the support another step, and thus changing the denomination of the actuating devices that have 120 been positioned. The lever 3 of the calculator is then operated and through the shaft 52 and cam 56, moves the stop carrier and causes a simultaneous operation of the selected keys of the calculator. Further movement of the lever 3 returns the carrier to its initial position by rotating the spindle 11 in a reverse direction until it is in the position shown in Fig. 8. On the reverse operation of the lever 3, the actuating de- 125 130

vices are returned to their normal positions by the resetting means already described.

The invention is not to be confined to the application in connection with a calculating machine such as shown in the illustrated construction, and my purpose has been only to illustrate the manner in which the improvements may be adapted to a conventional type of eighty-one key machine making it possible to control the entire eighty-one keys through a ten key mechanism. The invention may likewise be incorporated in a machine other than the eighty-one key type, and possibly involving other forms 15 of calculating units, and so far as my present invention is concerned, it is intended to cover the ten key controlling structure in order that it may be utilized to effect calculations without the necessity of any 20 additional controlling keys.

I claim as my invention:

1. In a calculating machine, the combination of a series of actuators, a traveling support, a series of actuating devices movably mounted thereon, a stop carrier, a series of stops movable thereon for controlling the position of the actuating devices, and means for moving the stop carrier relatively to the actuating devices to engage and 30 operate the actuators.

2. In a calculating machine, the combination of a series of actuators, a traveling support, a series of actuating devices movably mounted thereon, a stop carrier, a series of stops movably supported thereon, means for oscillating said stops for controlling the position of the actuating devices, and means for moving the stop carrier to move the actuating devices on the traveling 40 support to engage and operate the actuators.

3. The combination with a series of calculating units of a calculating machine, of a traveling or adjustable support, a series of actuating devices movably mounted on the support, an oscillatory stop carrier, a series of stops adjustably arranged on the carrier coöperating with and controlling the position of the actuating devices, and means for oscillating the stop carrier.

4. The combination with a series of calculating units of a calculating machine, of a traveling or adjustable support, a series of actuating devices movably mounted on the support, an oscillatory stop carrier, a series of oscillatory stops mounted on the carrier coöperating with and controlling the position of the actuating devices, and means for oscillating the stop carrier.

5. The combination with a series of calculating units, of a calculating machine, of a traveling or adjustable support, a series of actuating devices rotatively mounted thereon, an oscillatory stop carrier, a series of oscillatory stops mounted on the carrier coöperating with and controlling the posi-

tion of the actuating devices, and means for oscillating the stop carrier.

6. In a calculating machine, the combination of a series of actuators, a series of actuating devices adapted to coöperate therewith, a traveling support on which said actuating devices are movably mounted, a single stop normally locking the actuating devices against movement, means for oscillating said stop for successively releasing the actuating devices, a series of movable positioning stops, and means for oscillating a predetermined one of the positioning stops into the path of the actuating devices to selectively position the latter. 75

7. In a calculating machine, the combination of a series of actuators, an actuating device adapted to coöperate with a selected one of the actuators, a traveling support for said actuating device, a stop relatively to 80 which the support travels for normally locking said actuating device against movement on its support, means for moving said stop out of the path of the actuating device when the latter is in operating position, a series 90 of positioning stops, and means for oscillating a selected one of said stops into the path of the actuating device to arrest the latter in a predetermined position, when the actuating device is released from the locking 95 stop.

8. In a calculating machine, the combination of a traveling support, a series of actuating devices mounted thereon, means tending to move said actuating devices, a universal locking stop normally locking said actuating devices against movement, means for moving said locking stop to successively release said actuating devices, a series of positioning stops, and means for moving a selected one of the positioning stops into the path of movement of the actuating devices to arrest their movement at a predetermined point, when the locking stop is moved to release the actuating devices. 105

9. In a calculating machine, the combination with a support, of a movable actuating device mounted thereon, a locking stop normally in engagement with the actuating device to hold it against movement, means for 115 moving the locking stop out of engagement with the actuating device, an oscillatory carrier, a series of movable positioning stops mounted on the carrier, and means for moving any one of the positioning stops into the 120 path of the actuating device to stop the latter at a predetermined point.

10. In a calculating machine, the combination with a support, of a spring operated actuating device mounted thereon, a locking 125 stop normally in engagement with the actuating device to hold it against movement, an oscillatory carrier, a series of movable positioning stops mounted on the carrier, means for moving any one of said positioning stops 130

into the path of the actuating device to stop the latter at a predetermined point, and means controlled during the movement of the positioning stop operating to move the locking stop out of engagement with the actuating device.

11. In a calculating machine, the combination with a traveling support, of a movable actuating device mounted thereon, a locking stop normally in engagement with the actuating device to hold it against movement, means for moving the locking stop out of engagement with the actuating device, an oscillatory carrier, a series of movable positioning stops mounted on the carrier, means for moving any one of said positioning stops into the path of the actuating device to stop the latter at a predetermined point, and means controlled during the movement of the positioning stop operating to move the locking stop out of engagement with the actuating device.

12. In a calculating machine, the combination with a traveling support, of a spring controlled actuating device mounted thereon, a locking stop normally in engagement with the actuating device to hold it against movement, an oscillatory carrier, a series of movable positioning stops mounted on the carrier, means for moving any one of said positioning stops into the path of the actuating device to stop the latter at a predetermined point and means controlled during the movement of the positioning stop operating to move the locking stop out of engagement with the actuating device.

13. In a calculating machine, the combination of a plurality of movable actuating devices, a series of positioning stops with which said actuating devices are adapted to coöperate, a support movable relatively to said positioning stops on which said actuating devices are carried, means for moving said actuating devices on said support, and key controlled means for moving a selected one of said stops into position to engage an actuating device and, thereafter maintain said actuating device in numerical position.

14. In a calculating machine, the combination of a movable support, a plurality of actuating devices mounted thereon, means for moving said actuating devices on said support, a stop normally locking said devices against movement independently of the movement of the support, a carrier movable independently of and relatively to the movable support, a positioning stop mounted on the carrier, controlling means for oscillating said stop into the path of movement of the actuating device, and means for moving the locking stop out of the path of the actuating device when the positioning stop is moved into its path.

15. In a calculating machine, the combination of a support, a plurality of actuating

devices mounted thereon, means tending to move said actuating devices in one direction, a locking stop normally in the path of movement of said actuating devices, a movable stop carrier, a plurality of positioning stops mounted on said carrier, means for oscillating a selected one of said positioning stops into the path of movement of said actuating devices and simultaneously releasing one of said actuating devices, and means for moving the carrier to operate the actuating devices.

16. In a calculating machine, the combination with a support, of a plurality of actuating devices mounted on the support, a locking stop normally in engagement with the actuating devices to hold them against movement, a movable carrier, an oscillatory positioning stop mounted on the carrier, controlling means, and operative connections between the controlling means, the locking stop and the positioning stop whereby the positioning stop is moved into the path of the actuating device as the locking stop is moved out of its path, and means for moving the carrier relatively to the actuating devices.

17. In a calculating machine, the combination with a traveling support, of a plurality of spring controlled actuating devices mounted on the support, a locking stop normally in engagement with the actuating devices to hold them against movement, a carrier, an oscillatory positioning stop mounted on the carrier, controlling means and operative connections between the controlling means, the locking stop, and the positioning stop whereby the positioning stop is moved into the path of the actuating device as the locking stop is moved out of its path, and means for moving the carrier relatively to the actuating devices.

18. In a calculating machine, the combination with a rotary spindle having a cam way thereon, of a support, a projection on the support coöoperating with said cam way, a plurality of actuating devices mounted on the support, a locking stop, a positioning stop, means for moving the positioning stop into the path of the actuating device and the locking stop out of its path, and means operated simultaneously with the movement of the said stops for rotating the spindle.

19. In a calculating machine, the combination with a spindle having a cam way thereon, of a support mounted on the spindle, a projection on the support coöoperating with said cam way, a plurality of oscillatory actuating devices arranged on the support, a locking stop, an oscillatory carrier, a series of oscillatory positioning stops arranged on the carrier, means for moving any one of the positioning stops into the path of an actuating device and the locking stop out of its path, and means operated simultaneously

with the movement of said stops for rotating said spindle.

20. In a calculating machine, the combination with a spindle having a cam way thereon, of a support mounted on the spindle, a projection on the support coöperating with said cam way, a plurality of actuating devices arranged on the support, means controlling the positioning of the actuating devices, and instrumentalities controlled by the positioning of an actuating device operating to effect rotation of the spindle to advance said support.

21. In a calculating machine, the combination with a traveling support, of a plurality of spring controlled actuating devices rotatively mounted on the support, a locking stop normally in engagement with the actuating devices, a series of positioning stops, means for moving any one of the positioning stops into the path of an actuating device and the locking stop out of its path and resetting means operating to return the actuating device to its normal position, the locking stop being movable out of the path of the actuating device during its return to normal position.

22. In a calculating machine, the combination with a rotatively mounted actuating device having a locking portion, of a locking stop embodying an oscillatory bar engaging said locking portion and having a cutaway part to permit movement of the actuating device, a series of positioning stops, each comprising an oscillatory bar having a portion adapted to engage the actuating device, and means for moving the locking stop to permit release of the actuating device and simultaneously operating any one of the positioning stops to engage the actuating device.

23. In a calculating machine, the combination with a traveling support, of a plurality of spring controlled actuating devices mounted thereon, each including a locking portion, a locking stop embodying an oscillatory bar engaging said locking portion and having a cutaway part to permit movement of the actuating device, a series of positioning stops each comprising an oscillatory bar having a portion adapted to engage the actuating devices, and means for moving the locking stop to permit release of one of the actuating devices and simultaneously operating one of the positioning stops into position to engage the actuating device, the support being advanced during the operation of said stops to bring another actuating device into setting position.

24. In a calculating machine, the combination with a traveling support, of a plurality of spring controlled actuating devices mounted thereon, each including a locking portion, a locking stop embodying an oscillatory bar engaging said locking portion and

having a cutaway part to permit movement of the actuating device, a series of positioning stops each comprising an oscillatory bar having portions adapted to engage the actuating device, means for moving the locking stop to permit release of one of the actuating devices and simultaneously operating one of the positioning stops to engage the actuating device, the support being advanced during the operation of said stops to bring another actuating device into setting position, and resetting means for returning the actuating devices to normal position.

25. In a calculating machine, the combination with a traveling support, of a plurality of spring controlled actuating devices mounted thereon, each including a locking portion, a locking stop embodying an oscillatory bar engaging said locking portion and having a cutaway part to permit movement of the actuating device, an oscillatory carrier, a series of positioning stops mounted on the carrier, each comprising an oscillatory bar having a portion adapted to engage the actuating device, means for moving the locking stop to permit release of one of the actuating devices and simultaneously operating one of the positioning stops to engage the actuating device, the support being advanced during the operation of said stops to bring another actuating device into setting position, and means for operating the carrier.

26. In a calculating machine, the combination with a traveling support, of a plurality of spring controlled actuating devices mounted thereon, each including a locking portion, a locking stop embodying an oscillating bar engaging said locking portion and having a cutaway part to permit movement of the actuating device, an oscillatory carrier, a series of positioning stops mounted on the carrier, each comprising an oscillatory bar having a portion adapted to engage the actuating device, means for moving the locking stop to permit release of one of the actuating devices and simultaneously operating one of the positioning stops to engage said actuating device, the support being advanced during the operation of said stops to bring another actuating device into setting position, means for operating the carrier, and resetting means for returning the actuating devices to normal position.

27. In a calculating machine, the combination with a traveling support, of a plurality of spring controlled actuating devices mounted thereon, each including a locking portion, a locking stop embodying an oscillating bar engaging said locking portion and having a cutaway part to permit movement of the actuating device, an oscillatory carrier, a series of positioning stops mounted on the carrier, each comprising an oscillatory bar having a portion adapted to

- engage the actuating device, means for moving the locking stop to permit release of one of the actuating devices and simultaneously operating one of the positioning stops to engage said actuating device, the support being advanced during the operation of said stops to bring another actuating device into setting position, means for operating the carrier, and resetting means for returning 10 the actuating devices to normal position, the locking stop being movable out of the path of the actuating device during its return to normal position.
28. The combination with a series of calculating units, of a traveling or adjustable support, a series of actuating devices movably mounted on the support, a series of stops which are adjustable to coöperate with and determine the position of the actuating devices, and means acting to effect relative movement between said calculating units of the calculating machine and said actuating devices in order to move the calculating units in accordance with the position of the actuating devices.
29. The combination with a series of calculating units, of a traveling or adjustable support, a series of actuating devices rotatively mounted on the support, a series of oscillatory stops which are adjustable to coöperate with and determine the position of the actuating devices, and means acting to effect relative movement between said calculating units of the calculating machine and said actuating devices in order to move the calculating units in accordance with the position of the actuating devices.
30. The combination with operating units of a calculating machine, of a support, a spring operated actuating device mounted thereon, a locking stop normally in engagement with the actuating device to hold it against movement, a series of positioning stops, means for moving any one of said positioning stops into the path of the actuating device to stop the latter at a predetermined point, means controlled during the movement of the positioning device operating to move the locking stop out of engagement with the actuating device, and means acting to effect relative movement between said operating units of the calculating machine and said actuating devices in order to move the operating units in accordance with the position of the latter.
31. The combination with operating units of a calculating machine, of a spindle, a support movable on the spindle, a plurality of actuating devices adjustable on the support, a locking stop, a positioning stop, means for moving the positioning stop into the path of the actuating device and the locking stop out of its path, means operated simultaneously with the movement of said stops for changing the position of said sup-
- port on the spindle, and means acting to effect relative movement between said operating units of the calculating machine and said actuating devices in order to move the operating units in accordance with the position of the actuating devices. 70
32. The combination with operating units of a calculating machine, of a traveling or adjustable support, a series of actuating devices adjustably mounted on the support, a locking stop normally in engagement with the actuating devices, a series of positioning stops, means for moving one of the positioning stops into the path of an actuating device and the locking stop out of its path, resetting means operating to return the actuating device to its normal position after the operating units are moved, and means acting to effect relative movement between said operating units of the calculating machine and said actuating devices in order to move the operating units in accordance with the position of the actuating devices. 75 80 85
33. In a ten key type machine, the combination with a series of calculating units, of a traveling or adjustable support, a series of actuating devices movably mounted on the support, each of which actuating devices is arranged to selectively coöperate with any one of the calculating units which it is designed to engage, and a series of stops coöoperating with the actuating devices for controlling their position. 90 95
34. In a ten key type machine, the combination with a series of calculating units, of a traveling or adjustable support, a series of actuating devices movably mounted on the support, each of which actuating devices is arranged to selectively coöperate with any one of the calculating units which it is designed to engage, and a series of oscillatory stops coöperating with the actuating devices and controlling their position. 100 105
35. In a ten key type machine, the combination with a series of calculating units, of a traveling or adjustable support, a series of actuating devices rotatively mounted on the support, and a series of oscillatory stops coöperating with and controlling the positions of the actuating devices. 110 115
36. In a ten key type machine, the combination with a series of calculating units, of a traveling or adjustable support, a series of actuating devices movably mounted on the support, and a series of oscillatory stops coöperating with and controlling the position of the actuating devices. 120
37. The combination with a series of calculating units, of a traveling support, a series of actuating devices mounted on the support, and a series of oscillatory positioning stops governing the position of the actuating devices. 125
38. The combination with a series of calculating units of a traveling support, a plu- 130

rality of actuating devices mounted on the support, an oscillatory locking stop, and a series of oscillatory positioning stops governing the positions of the actuating devices.

39. The combination with a series of calculating units, of a traveling support, a plurality of actuating devices mounted on the support, a series of positioning stops governing the positioning of the actuating device, and means operated simultaneously with the movement of each of said stops for advancing the traveling support.

40. The combination with a series of calculating units, of a traveling support, a plurality of actuating devices mounted on the support, a locking stop, a series of oscillatory positioning stops controlling the positioning of the actuating devices, and means operated simultaneously with the movement of said locking stop for advancing the traveling support.

41. In a calculating machine, the combination with a movably mounted actuating device having a locking portion, of a locking stop embodying an oscillatory member engaging said locking portion and having a cutaway part to permit movement of the actuating device, and a series of positioning stops, each comprising an oscillatory member having a portion adapted to engage the actuating device, and means for moving the locking stop to permit release of the actuating device and simultaneously operating any one of the positioning stops to engage the actuating device.

42. In a calculating machine, the combination of a plurality of actuators arranged in numerical and denominational positions, a series of actuating devices adapted to co-operate therewith, means for moving said series of actuating devices step by step into predetermined denominational position, means for moving said actuating devices one by one in another direction, and a single series of cylindrical stops for limiting movement in the latter direction and controlling their numerical positions in any denominational positions which they may assume.

50 43. In a calculating machine, the combination of a plurality of actuators, a series

of actuating devices adapted to co-operate therewith, means for moving said actuating devices in numerical position, and a stop adapted to simultaneously control the numerical position of a plurality of said actuating devices.

44. In a calculating machine, the combination of a plurality of actuators, a series of actuating devices adapted to co-operate therewith, means for moving said actuating devices step by step into denominational position, means for moving said actuating devices in another direction into numerical position, and a series of stops relatively to which the actuating devices move in both directions and adapted to control their numerical positions in all denominational positions.

45. In a calculating machine, the combination of a support, a plurality of actuating devices movably mounted thereon, means for moving said actuating devices, a single stop for holding said actuating devices against movement, a series of positioning stops normally out of the path of movement of said actuating devices, and means for moving said stop to release said actuating devices and simultaneously moving a positioning stop into the path of movement of said devices.

46. In a calculating machine, the combination of a traveling support, a plurality of actuating devices movably mounted thereon, and a single stop for locking said devices in normal position movable to permit movement of one actuating device while holding another actuating device against movement.

47. In a calculating machine, the combination of a series of actuators, a series of actuating devices adapted to co-operate therewith, a rotatable stop normally locking said devices against movement, and means for rotating said stop into a position to release a single actuating device and into another position to permit movement of all said actuating devices.
